(57) **CLAIM**

The ornamental design for a charger, as shown and described.

DESCRIPTION

FIG. 1 is a front, top, and left side perspective view of a charger showing the new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof;

FIG. 7 is a left side elevational view thereof;

FIG. 8 is a front, bottom, and left side perspective view thereof; and,

FIG. 9 is a front elevational view thereof in an open position. The broken lines in FIG. 9 show portions of the charger that do not form part of the claimed design.

1 Claim, 9 Drawing Sheets
